STEAM SUPERHEATER

John H. Brown, Springfield, Mo.

Original application June 12, 1939, Serial No. 278,767. Divided and this application June 13, 1940, Serial No. 340,349

2 Claims. (Cl. 122—460)

This invention relates to steam superheaters of the heating tube type designed for use in conjunction with steam generators.

An important object of my invention is to provide a steam superheater of simple and economical construction adapted to be readily assembled with a steam generator of the type disclosed in my copending application Serial Number 278,767 (now Patent No. 2,207,654 granted July 9, 1940), 10 of which the present application is a division.

Another object of my invention is to provide a steam superheater of the above character so constructed and arranged as to cause the steam entering the superheater from the boiler to impinge upon a baffle to remove excessive moisture therefrom and return this moisture to the boiler.

Still another object of my invention is to provide a superheater of the above character in which the heating tubes are interposed in line with the flue carrying off the waste combustion gases from the steam generator so that these hot gases are caused to flow across the tubes at a steep angle, such as is conducive to the most efficient transfer of heat from the gases to the steam flowing 25 through the tubes.

Other objects and advantages will be apparent from the following detailed description of a preferred embodiment of the invention, reference being had to the annexed drawing in which:

30 Figure 1 is a side elevational view of a steam generator having a superheater associated therewith;

Figure 2 is an end view of the superheater of Fig. 1; and

35 Figure 3 is a vertical cross-sectional view of the superheater and showing its manner of assembly with the top of the steam generator.

Referring now to the drawing, in Fig. 1 is illustrated a steam generator G upon the top which is 40 associated a superheater S. The steam generator is more particularly described in my copending application above-referred to and includes a neck I projecting above the top of the generator and constituting a flue or stack for carrying off the 45 waste combustion gases from the burner that is used for heating the generator.

The superheater comprises a horizontally disposed metal drum 2 closed at both ends by dished end plates 3 bolted to circumferential flanges upon the ends of the drum. A sleeve 4 surrounding an opening through the wall of the drum intermediate its length telescopes over the upper end of the neck I which projects above the generator, thus affording direct communication 55 between the neck and the interior of the drum.

A pair of transverse laterally-spaced partition plates 5 and 5a divide the drum into three compartments, namely a steam inlet compartment 6 at one end of the drum, an intermediate flue compartment 7, which is in communication with the neck through sleeve 4, and a steam outlet compartment 8 located at the other end of the drum. The steam inlet compartment communicates with the steam generator through a pair of flanged couplings 9 and 9a which are bolted together and 5 which together extend vertically between an opening in the top or steam dome of the generator and an opening through the circumferential wall of the drum.

Extending longitudinally through the flue compartment 7 and opening through the partition plates 5 and 5a are a series of heat transfer tubes 10 for the passage of steam from the steam inlet compartment 6 into the steam outlet compartment 8. The flue compartment at one end has 20 an offtake 11 which may lead to a stack venting to the atmosphere. A baffle 12 is suitably provided in the steam inlet compartment in the path of the steam from the generator to remove moisture carried in suspension, and such moisture may 25 drain back into the generator through the couplings 9 and 9a.

The arrangement is such that the waste flue gases leaving the steam generator by way of the neck I enter the flue compartment 7 of the superheater where they flow across the heat transfer tubes 9 at approximately right angles thereto and give up a large part of their residual heat to these tubes and hence to the steam passing through the tubes. The offtake 11 is located out-of-line 30 with the neck I so as to insure the complete bathing of the tubes by the flue gases before the latter leave the compartment.

The steam from the steam generator enters the steam inlet compartment through the straight 40 vertical passageway provided by the flanged couplings 9 and 9a. This steam impinges upon the baffle plate 12 so that the moisture carried in suspension is given up by the steam and collects on the baffle plate from which it drips into the 45 bottom of the compartment and eventually drains back into the steam generator. The temperature of the steam in passing through the heat transfer tubes is raised and upon entering the steam outlet compartment is drier and hotter than when it entered the tubes.

This hot steam leaves the steam outlet compartment 8 via a duct 13 leading off from this compartment and communicating with the system to which the steam is to be furnished, as for 55

example a house heating system. The superheater may be marketed as a separate unit for assembly with steam generators of the general type described or the superheater may form a 5 unitary part of the generator. In any event the construction is simple and its operation efficient. By simply removing the end plates 3 access is provided to the tubes for cleaning or repair.

Manifestly the invention is capable of embodiment in forms other than that described above 10 which is to be regarded as exemplary rather than as restrictive of the invention.

I claim:

1. A steam superheater comprising a cylindrical drum adapted to be disposed in a horizontal position, dished end plates removably bolted to and closing the ends of the drum, a pair of partition walls dividing said drum into a steam inlet compartment, an intermediate flue 15 compartment and a steam outlet compartment, a series of heat-transfer tubes extending between and opening through the partition walls, a passage opening through the circumferential wall of the drum for the introduction of hot flue gases 20 into the flue compartment in a direction at approximately right angles to the heat-transfer tubes, a sleeve surrounding said passage externally of the drum and adapted to encircle and engage a flue for supporting the superheater in 25 position, an offtake opening through the circumferential wall of the drum upon the opposite side of the drum from said passage but laterally offset therefrom for the removal of flue gases from 30 said flue compartment, an opening through the circumferential wall of the steam inlet compartment for the introduction of steam therein and the removal of condensate therefrom, a baffle 35 within said steam inlet compartment located at an angle to and in line with said opening, and a

duct leading off through the circumferential wall of the steam outlet compartment for the removal of steam therefrom.

2. The combination with a steam generator of the type having a vertically disposed neck constituting a flue for leading off the waste flue gases from the generator, of a steam superheater adapted to be supported in horizontal position above the generator, said superheater comprising a cylindrical drum, dished end plates removably bolted to and closing the ends of the drum, a pair of partition walls dividing said drum into a steam inlet compartment, an intermediate flue compartment and a steam outlet compartment, a series of heat-transfer tubes extending between and opening through the partition walls, a passage opening through the circumferential wall of the drum for the introduction of hot flue gases into the flue compartment in a direction at approximately right angles to the heat-transfer tubes, a sleeve surrounding said passage and adapted to encircle and engage the neck of the steam generator for supporting the superheater in position, an offtake opening through the circumferential wall of the drum approximately diametrically located with respect to said passage for the removal of flue gases from 10 said flue compartment, an opening through the circumferential wall of the steam inlet compartment for the introduction of steam therein, a baffle within said steam inlet compartment located at an angle to and in line with said opening, coupling members providing communication between said opening and the steam generator, and a duct leading off through the circumferential wall of the steam outlet compartment for the removal of steam therefrom. 15

JOHN H. BROWN.
